SIGNAL ATTACHMENT FOR FLASHLIGHTS

Frederick E. Burdick, New London, Conn.

Application February 2, 1950, Serial No. 141,894

2 Claims. (Cl. 177—329)

1

This invention relates to improvements in a signal attachment for a conventional flashlight. Heretofore, signal attachments have been devised for use with conventional flashlights, such attachments being used for numerous signaling purposes such, for example, as by police officers in directing traffic, particularly in dark areas at the scene of an accident or otherwise. Such previously used attachments have, in general, been of a cumbersome and unhandy nature, however, due to the fact that they are of a stiff nature and project beyond the lamp end of the flashlight an appreciable distance, whereby the same cannot readily be carried upon the person of the user, such as a police officer. Further, the nature of the signal attachment has been such that they are subject to fracture and breakage upon the same being bumped into hard surfaces and objects. Also, when attached to a flashlight for signaling purposes, the flashlight is not readily usable for illuminating purposes other than for signaling unless the attachment is first detached from the flashlight.

It is an object of the present invention to provide a signal attachment which may be quickly secured to the lamp end of a conventional flashlight, said attachment being flexible, whereby the same may be readily folded over the outer end against the sides of the flashlight casing when not in use, thus rendering the flashlight and attachment readily capable of being carried upon the person of the user in a coat or trousers pocket, for example.

It is another object of the invention to provide a signal attachment which may be colored for displaying a suitable signal color such as red, the construction being such, however, that the clear white light of the flashlight may be displayed for illuminating purposes upon any desired surface or object without removing the attachment from the flashlight and without disarranging the attachment relative to the position in which the attachment is used for signaling purposes.

It is a further object of the invention to provide signaling attachment for flashlights which may be quickly and securely attached to the lamp end of a conventional flashlight in such manner that the flexible material substantially surrounds the lamp end of the flashlight and extends a substantial distance therebeyond, the flexible material being held in extended, substantially cylindrical condition whereby the flashlight and attachment may be waved torch-like, if desired, for signaling purposes.

It is still another object of the invention to

provide a flexible signal attachment for a flashlight which is rugged and durable in use and capable of long life even though subjected to numerous foldings such as when the attachment is folded against the sides of the flashlight for storage purposes when not in use.

Details of these objects and of the invention, as well as other objects thereof are set forth in the following specification and illustrated in the accompanying drawing forming a part thereof, said drawing being for purposes of illustration only, however, and is not to be considered restrictive.

Referring to the drawings:

Fig. 1 is a side elevation of a flashlight having attached thereto in extended operative position a signal attachment embodying the present invention.

Fig. 2 is a transverse sectional view of the signal attachment taken on the line 2—2 in Fig. 1.

Fig. 3 is a view similar to Fig. 1 but showing the flashlight and attachment in a position rotated 90° from the position thereof shown in Fig. 1 and the attachment being illustrated in full lines in folded position and, in dot and dash lines, in extended operative position.

Fig. 4 is a fragmentary view similar to Fig. 1 and illustrating another embodiment of signal attachment applied to the end of a flashlight, part of said attachment being broken away to illustrate details thereof.

Fig. 5 is a transverse sectional view of the signal attachment shown in Fig. 4 and taken on the line 5—5 thereof.

Referring to the details illustrated on the drawing, a conventional flashlight 10 of the portable hand type is illustrated as being substantially cylindrical. It is to be understood, however, that the shape of the flashlight body may vary from a cylindrical exterior and may, for example, be polygonal in cross section. Also, in the exemplary embodiment of flashlight illustrated in the drawings, the lamp end 12 thereof is belled somewhat and at its outer end has a slightly larger diameter than that of the body thereof, thus providing a tapered or frusto-conical section 14 which connects the lamp end of the flashlight to the body thereof. A conventional switch 16 projects slightly from the exterior surface of the body of the flashlight 10.

The signal attachment embodying the present invention is adapted for use with the flashlight 10 and comprises a sheath-like signal member 18 which is preferably made from a substantially rectangular or square sheet of flex-

ible, translucent or transparent synthetic resinous material of which polyethylene is one example which has been found to be highly suitable. The material from which the member 18 is formed is also tough so as readily to permit folding without being torn, cracked, or rendered unusable for the purposes to be described.

The sheet of material from which signal member 18 is formed is folded around a longitudinal axis so as to present a somewhat tubular configuration when attached to the flashlight 10 as illustrated in the figures of the drawing. Two of the opposite edges of the sheet of material are overlapped adjacent one end thereof to form a tubular portion, as clearly illustrated in Figs. 1 and 4 particularly, and said overlapped position of the material is maintained by a band 20 of suitable flexible tape which is cemented or otherwise affixed to the exterior of the overlapped material so as to maintain the same in tubular formation at said one end of the member 18 as shown in cross-section in Fig. 2.

The band 20 may be formed from material which is either slightly elastic or inelastic. The circumference of the band is preferably slightly less than the outer diameter of the lamp end 12 of the flashlight, whereby said band 20 will render the member 18 capable of being attached to the lamp end of the flashlight 10 by slidably moving the member 18 upon the flashlight from the rear end thereof. The tubular end portion of the member 18 surrounded by the band 20 will be brought into engagement with the belled section 14 of the flashlight and will prevent further movement of the member 18 forwardly relative to the flashlight. The signal member 18 is of such length that the forward end 22 thereof will extend a substantial distance forwardly from the lamp end of the flashlight and the edges 24 of the sheet of material from which the member 18 is formed will extend divergently away from each other as clearly illustrated in Figs. 1 and 4.

Due to the tapered or conical formation of the belled section 14 of the flashlight 10 engaging the tubular end of the signal member 18 during the assembly of the signal member to the flashlight, the edges 24 of the signal member will be spread divergently apart as illustrated in Figs. 1 and 4. The opposite end of the signal member extends rearwardly from the band 20 and is shaped to provide opposed skirt-like members 26 which are brought into snug engagement with the sides of the casing when the tubular end of the signal member is slidably moved into engagement with the belled end 14, as clearly illustrated in Fig. 1. Such snug engagement of the members 26 of the signal member 18 with the sides of the flashlight casing serve to stiffen the signal member 18 in a manner to hold the forward end 22 of said signal member in extended position forwardly beyond the lamp end 12 of the flashlight 10, whereby said forward end will be held in such extended position as illustrated in Fig. 1 even though the flashlight is waved torch-like during use. However, the flexibility of the material from which the signal member is formed will also permit a certain amount of waving of the signal member relative to the flashlight to thereby somewhat resemble a waving flame and thus enhance the signaling effect. The separation of the edges 24 of the forward end portion 22 also enhances this function of the signal member 18.

The band 20 and signal member 18, being flex-

ible, may readily be folded in flat condition when detached from the flashlight, whereby the signal member may be stored or shipped in compact, flat, folded condition. Further, the circumference of the band 20 and the tubular portion of the signal member 18 adjacent the band is such that the signal member may readily be slipped onto the flashlight casing and permit passage of the member 18 over the switch 16 of the flashlight during such attachment of the member 18 thereto.

The signal member 18, when not in use, may remain attached to the flashlight 10 if desired and the flexibility of the member 18 permits the same to be folded over the forward end of the flashlight and into close engagement with the body thereof as indicated in full lines in Fig. 3. In such condition, the flashlight and signal member may readily be carried upon the person of the user in a coat or trousers pocket without in any way damaging the signal member or flashlight and the signal member may be quickly withdraw from such pocket and be ready for instant use. The normally forward end 22 of the signal member, when folded backward over the flashlight body as shown in Fig. 3 will frictionally engage the interior of such pocket, whereby upon withdrawal of the flashlight from the pocket, the signal member 18 will automatically be extended in operative position during such withdrawal. However, if the signal member is not automatically extended as aforesaid, a simple, quick shaking of the flashlight will cause the signal member to be extended immediately into operative position as indicated in Fig. 1 or in dot and dash lines in Fig. 3.

It will also be noted that during use the forward outer end of the signal member 18 is open and such open end, as well as the space between the diverging edges 24 of the signal member, will permit conventional white light from the flashlight to shine forwardly from the flashlight. Such white light may be directed against any desired object or surface for purposes of viewing the same with the same efficiency as if the signal member were not attached to the flashlight. No removal of the signal member from the flashlight is necessary to use the light for such purposes.

The signal attachment may also be provided with a rearward end similar to that shown in Fig. 4, wherein the signal member 18 is constructed so that the rearward edge 28 thereof is folded over upon itself for purposes of enclosing an endless elastic band 30, formed from rubber or otherwise, and the rearward edge 28 is maintained in folded position by any suitable means such as a band of tape 32 which may be secured over the folded rearward edge 28 and the outer surface of member 18 by cement or otherwise as clearly shown in the sectional portion of Fig. 4. Details of this construction will be further understood from Fig. 5 which shows a sectional view thereof. As in the construction shown in Figs. 1 and 2, the edges of the sheet from which the signal member 18 is formed are overlapped adjacent one end to provide a tubular rearward end on the signal member 18 which surrounds the forward end of the flashlight casing and the elastic band 30 will contract said tubular end of the signal member into frictional engagement with said forward end of the flashlight casing. The embodiment shown in Fig. 4 may not only be used on a flashlight having a belled forward end, but the same may also be readily attached to the forward end of a flashlight having a cylindrical casing of sub-

stantially uniform diameter throughout its length. Otherwise all other functions of the embodiment of signal member 18 shown in Fig. 4 are substantially similar to the embodiment thereof shown in Figs. 1 through 3.

It will thus be seen that the signal member comprising the present invention which is attachable to the forward end of a conventional flashlight is highly useful for signaling purposes by such persons as policemen and firemen for directing traffic or for use as road flares while making repairs or changing tires on a vehicle. The same may also be used in scouting for night signaling of code messages. Further, if one longitudinal half of the signal member is colored green, for example, and the other longitudinal half is colored red, the signal member may readily be used as a boat light. If desired, the sheet-like material from which the signal member is formed may be manufactured so as to have a pebbled or so-called waffle finish, or the material may be formed so as to have spaced shallow ribs or pleats extending longitudinally of the signal member when in use, thus aiding in diffusing the light and enhancing the signaling properties thereof. When ribs or pleats are formed in the material the same will also serve to somewhat stiffen the material and thus aid in maintaining the signal member in longitudinally extended position as shown in Figs. 1 and 4.

The flexibility and foldable nature of all parts of the signaling member also permits the same readily to be folded over the forward end and against the sides of the flashlight so that the same may be stored, while attached to the flashlight, within a small compact space such as within a pocket of the clothes of a user or within the glove compartment of a vehicle without danger of breakage and without being bulky or adding noticeably to the size of a conventional flashlight. The signal member may also be used in inclement weather without being harmed or deteriorated and without impairing the signaling qualities of the member. Further, due to the open outer end of the signal member and open slit extending longitudinally inward from the forward end thereof, the flashlight may readily be used for conventional illuminating purposes for which flashlights are customarily used without requiring the detachment or rearrangement of the signal member from its normal operative position on the flashlight.

While the invention has been illustrated and described in its preferred several embodiments and has included certain details, it should be understood that the invention is not to be limited to the precise details herein illustrated and de-

scribed since the same may be carried out in other ways, falling within the scope of the invention as claimed.

I claim as my invention:

1. For use with a conventional flashlight having a belled end of greater maximum diameter than the body of the flashlight, a signal member comprising a sheet of flexible foldable light-penetrable material and having opposite edges of said sheet folded into overlapping relationship adjacent one end to provide a tubular portion disposable around the belled end of said flashlight, a band surrounding said tubular portion configuration and attached thereto, said band having a smaller circumference than that of the outermost part of said belled end of said flashlight, and skirt-like members integral with said signal member and extending beyond said band in a direction away from the lamp end of said flashlight when said signal member is attached thereto, the engagement of said tubular portion of said member with said belled end of said flashlight casing serving to urge said skirt-like members into firm engagement with said flashlight casing to thereby brace the opposite end of said signal member in extended substantially cylindrical position forwardly from the lamp end of said flashlight.

2. Signal means attachable to the lamp end of a flashlight comprising a sheet of foldable light-penetrable material rolled into a generally tubular section adjacent one end thereof with the opposite edges overlapping, said generally tubular section being disposable about the lamp end of a flashlight, a band embracing said tubular section and said lamp end to securely clamp said tubular section to said lamp end, the other end of said sheet providing a generally cylindrical skirt extending beyond the lamp end of the flashlight, said skirt being braced in extended position by clamping engagement of said tubular section and the casing of the flashlight and said skirt being foldable over the lamp end against the casing to permit compact storage of the flashlight and signal means while operatively connected.
